UNITED STATES PATENT OFFICE.

JOSEPH IACONO, OF NEW YORK, N. Y.

SPARK-PLUG.

1,834,377.

Specification of Letters Patent. Patented Mar. 23, 1920.

Application filed July 31, 1919. Serial No. 314,429.

To all whom it may concern:

Be it known that I, JOSEPH IACONO, a subject of Italy, (who has declared his intention of becoming a citizen of the United States,) residing at the city of New York, borough of Manhattan, State of New York, have invented a certain new and useful Spark-Plug, of which the following is a specification.

10 This invention is a spark plug for use in engines of the internal combustion type, and it is directed more particularly to improving the device disclosed in a prior patent granted to me June 17, 1919, No. 1,306,817.

15 In the device of my prior patent, the body of the plug is slotted for the reception of a rotatable terminal. In one part of the present invention I seek to simplify the construction and to secure economy in the manufacture by omitting the slot in the plug, and to these ends I resort to the use of a hanger for the rotatable terminal, whereby said hanger may easily be attached to the body of the plug for mounting the rotatable terminal into coöperative relation to the fixed terminal.

20 Another part of the invention consists in a novel form or construction of the rotatable terminal, the body of which is provided with radial shoulders on the respective faces or sides, and the outer edge of which is formed with a series of abutments positioned tangentially to the otherwise circular peripheral edge of said rotatable terminal.

25 Other features and advantages of the invention will appear from the following description taken in connection with the drawings, wherein—

Figure 1 is a side elevation of a spark plug constructed in accordance with my present invention.

Fig. 2 is a sectional elevation, the plane of the section being indicated by the dotted line 2—2 of Fig. 1, looking in the direction of the arrow.

Fig. 3 is a detached view of the rotatable terminal, the same being an edge elevation viewed in the direction of the arrow 3 in Fig. 1, and

Fig. 4 is a detached view of one form of the hanger composed of complementary parts, the rotatable terminal being shown in dotted lines.

The body, A, of the plug is externally threaded, at a, for attachment to the cylinder or other fixed part of the engine, said

body being of hexagonal formation, at a', for the application of a wrench or other implement. As is usual in the art, the plug is provided with an insulating member B for the accommodation of a rod C which constitutes the fixed terminal, and this member B is retained fixedly in the body A by the usual gland D.

According to the present invention, the body A is free from the slot employed in the device of my prior patent for the reception of the rotatable terminal. As shown in Fig. 2, the inner end portion of the plug-body is chambered at b in order to receive the corresponding end portion of the fixed terminal C, and in the wall of said chambered portion the plug-body is provided with openings, c, the latter being drilled or bored to a suitable depth, said openings c being parallel to the longitudinal axial line of the plug-body.

D is a hanger for mounting the rotatable terminal E in a position below the chambered end c of the body and in coöperative relation to the fixed terminal C. As shown, the hanger is composed of a single piece of suitable material, such as wire, and the same is bent, or otherwise formed, to produce a journal d, the attaching arms, d', and a shank, e. The wire composing the hanger is first bent at two points to form the members constituting the shank e and the part which acts as the journal d, after which the wire is again bent so as to form the arms d', the latter being spaced apart a distance greater than the length of the journal and said arms being parallel. Prior to attaching the hanger to the plug-body, the rotatable terminal E is positioned on the journal d, after which the arms d' of said hanger are thrust into the openings c of the plug-body, suitable means being employed for fixedly attaching said arms d' to the body A, whereby the hanger occupies a permanent relation to the spark plug. As shown in Fig. 2, the hanger is bent from, or composed of, a single piece of wire, but for conveniently assembling and attaching the rotatable terminal, I

may and preferably do, resort to the construction of hanger shown in Fig. 4, wherein I have illustrated said hanger as composed of complementary parts D', D' so bent that the meeting ends of the wires constitute the journal d for the rotatable terminal.

The rotatable terminal or electrode, is a single piece of iron, steel, or other current-

carrying metal: in form, it is approximately a disk, and at the center it is provided with an opening and flanged to produce a hub *f*, whereby the terminal is adapted to be fitted loosely on the journal *d* of the hanger *D* or *D'* so as to turn freely thereon under the flow or pressure of the gases within the engine cylinder. The peripheral portion of the rotatable terminal is notched or cut away at a number of places, as indicated at *g*, in Fig. 1, said peripheral edge of the said member being bounded by lines *h*, *i*, whereof the lines *h* are tangents to the otherwise circular outline of the approximately disk shaped member. On the side (lateral) faces of the disk, it is formed with ribs or shoulders *j*, the latter extending radially to the hub *f* and extending, also, past the tangential edges *h* so as to meet with the edges *i*, thereby producing a succession of abutments *k*, the latter being positioned to extend inwardly from the periphery of the disk shaped electrode. The radial shoulders and the peripheral abutments present surfaces for the action of the gases flowing within the engine cylinder, so that the flow of the gases will impart the desired rotary movement to the electrode *E*. The abutments at the periphery of the rotatable terminal are adapted to travel in a path close to the extremity of the fixed terminal *C*, and to produce therewith a succession of spark gaps across which the current is compelled to jump and thereby produce a succession of sparks, the intensity of which is augmented by the rotation of the abutments with respect to the fixed position of the electrode *C*.

It is thought that the operation of the de-

vice, and the advantages thereof, will be understood from the foregoing description taken in connection with the drawings.

Having thus fully described my invention; what I claim as new and desire to secure by Letters Patent is:—

1. A spark plug comprising a body member, a fixed electrode therein, a hanger composed of complemental parts attached to the body member and positioned for the meeting ends of said parts to constitute a journal, and a rotatable electrode mounted loosely on the journal and supported by the hanger in co-operative relation to the fixed electrode.

2. In a spark plug, a rotatable terminal or electrode provided with radial shoulders and having a notched periphery so formed as to present a series of abutments.

3. In a spark plug, a rotatable electrode provided upon its respective faces with radial shoulders, the edge portion of said electrode being formed with notches extending inwardly and meeting with said radial shoulders and forming therewith a succession of abutments.

4. In a spark plug, a rotatable electrode the edge portion of which is provided with a series of notches and the respective sides of which are provided with ribs or shoulders so related to the notches as to produce therewith a succession of abutments upon the peripheral portion of said electrode.

In testimony that I claim the foregoing as my invention I have signed my name hereto at the city of New York this 24th day of July, 1919.

JOSEPH LA CONO.
